UNITED STATES PATENT OFFICE.

ANDREW E. MILLER, OF BALTIMORE, MARYLAND, ASSIGNOR TO NATIONAL COMPOSITION TYPE COMPANY, OF BALTIMORE, MARYLAND, A CORPORATION OF DELAWARE.

TYPE-CASTING MACHINE.

968,383.

Specification of Letters Patent. Patented Aug. 23, 1910.

Application filed May 26, 1909. Serial No. 498,520.

To all whom it may concern:

Be it known that I, ANDREW E. MILLER, of Baltimore, in the State of Maryland, have invented certain new and useful Improvements in Type-Casting Machines, of which the following is a specification.

This invention relates to the art of type making in which is produced individual type characters, such as body and display letters, borders, ornaments, spaces, quads and the like, that are used in type composition.

Heretofore the business of the type founder and printer have been conducted separately and wholly distinct. The printer has been dependent upon the type founder for supplies of movable type, and in consequence the procuring of "sorts" or the addition to fonts of only a portion of its type characters has been attended with inconvenience, delay and expense.

The present invention has for one of its objects to overcome these difficulties by extending the domain of the printer by enabling him, in addition to producing the printed matter, to produce the type instrumentalities by which that matter may be obtained.

A further object is to advance the art by enabling the printer to maintain perfectly faced type, whereby the printed product is always of the highest standard.

A further object is to provide a machine capable of producing various sizes and styles of type of the highest standard quality; to replenish "sorts" at will; and to permit the recasting of old and worn out type into new and more desirable faces.

A further object is to provide such an organization or combination of the principal elements involved as will enable the desired type to be produced without expert knowledge of type founding.

A further object is to produce a mold constructed of a minimum number of parts and so arranged as to permit of rapid adjustment for changes in the size of the type body, or of the character on said body, without necessitating the employment of expert type founders.

A further object is to provide improved means for regulating the size of the mold cavity, whereby the changes in the size of the cast may be readily and quickly accomplished.

A further object is to provide a mold capable of casting type bodies of all sizes and styles, and means arranged to automatically conform to the differences in size of the cast for securely closing the mold cavity during each casting operation.

A further object is to provide a mold formed of loosely mounted, normally stationary sections, and means for rigidly locking the same, said locking means being adjustable to conform to changes in the size of the mold cavity.

A further object is to provide means whereby the size or style of the cast may be readily and quickly changed at will, and the casting operation carried on at relatively high speed irrespective of the size or style of the cast.

A further object is to provide improved means for ejecting the type after each casting operation.

A further object is to provide an improved mold slide for closing the mold cavity.

A further object is to provide improved means for breaking the jets from the type after the latter have been ejected from the mold.

A further object is to provide improved means for accurately placing the matrix in proper position with relation to the mold cavity.

A further object is to provide improved means for injecting molten metal into the mold cavity.

A further object is to provide improved means for operating the various moving parts in time with each other, and to so construct said parts as to automatically adjust themselves to changes in the size of the mold cavity.

The invention will be hereinafter fully set forth and particularly pointed out in the claims.

In the accompanying drawings:—Figure 1 is a side elevation of a type casting machine embodying my invention. Fig. 2 is a similar view from the opposite side. Fig. 3 is a top plan view. Fig. 4 is a vertical sectional view. Fig. 5 is a top plan view with the matrix mechanism removed. Fig. 6 is an enlarged top plan view of the mold and its adjuncts. Fig. 7 is a detail view of a portion of the mold. Fig. 8 is a detail sectional view illustrating the method of cooling the mold. Fig. 9 is a detail plan view

of the mold slide. Fig. 10 is a front end view of the mold and its adjuncts, parts being in section. Fig. 11 is a similar view with the mold slide advanced to open the 5 end of the mold. Fig. 12 is a detail sectional view of the mold and its support. Fig. 13 is a sectional view illustrating the matrix carrier. Fig. 14 is a top plan view of the mold base. Fig. 15 is an end view 10 thereof. Fig. 16 is a detail view of the type guide. Fig. 17 is a view of the pump locking mechanism. Fig. 18 is a view illustrating the mechanism for operating the rock shafts in time. Figs. 19 and 20 are details. 15 Referring to the drawings, 30 designates the supporting base or standard provided with an upper platform or extension 31.

The power mechanism comprises a power shaft 32 mounted in base 30 and geared with 20 a driving motor 33 of any preferred construction. Power is transmitted from the shaft 32 by a pulley 34 mounted thereon and controlled by a clutch 35 operated by a lever 36, as shown. It will be understood, however, that I do not limit myself to any particular form of power mechanism, the form 25 shown being merely for illustrative purposes.

The mold mechanism comprises a mold 30 base 40 pivoted to the platform or extension 31, and supporting two mold blocks 41, 42, the latter being adjustably mounted. The base 40 is provided with shoulders or abutments 43, 44, between which the mold blocks 35 are placed. Interposed between the section 42 and the shoulder 44 is a filler block 45, which is of such proportions as to give the proper bodywise size to the mold cavity 46. In this connection it will be noted that a 40 plurality of filler blocks 45 of different predetermined sizes, conforming to the various body-wise sizes of standard type, are employed, said filler blocks being interchangeable. Thus in order to secure the proper 45 body size of the mold it is only necessary for the operator to select the proper filler block and insert the same in a manner to be later described. The jet cavity 47 is formed by jet plates 48 located in a recess in base 40 below the mold sections 41, 42. A filler 50 block 49 similar to the block 45 may be employed to adjust the size of the jet cavity when such adjustment is desired. I prefer, however, to employ a jet cavity of uniform 55 size for all sizes of the body cavity. The nipple plate 50 is located below the jet plates, and the mold section 42 is provided with a rib 51 adapted to form the usual nick in the type body. The mold section 41 is 60 held normally stationary by means of a finger 52 secured to a segmental member 53 carried by a rock shaft 54, said finger engaging a notch 55 in the top face of said block. The member 53 is arranged to abut 65 against a similar member 56 rigidly secured

to the mold base, each of said members being provided with a series of holes 57 arranged on an arc of a circle. Said holes are so positioned relative to each other that they are normally out of register, whereby the 70 tension on spring 58 may be adjusted by bringing any two of said holes into register and passing a screw or bolt 59 through them. (See Figs. 1, 2, 3 and 10.) Said spring encircles the shaft 54 and through the medium 75 of finger 52 acts to hold the mold block 41 normally against the ejector 60. The ejector 60 is mounted to reciprocate between the sections 41, 42 of the mold, said ejector being of a thickness conforming to the proper 80 body size of the type that it is desired to cast, and definitely proportioned with relation to the filler block 45. A plurality of such ejectors are employed, each of different body size, and interchangeable, whereby one 85 may be substituted for the other when it is desired to change the body side of the cast. The jet ejector 61 is mounted in the jet cavity 47. The type ejector 60 is provided with a notch 62 adapted to fit over the T-end 90 63 of a reciprocating crosshead 64, the jet ejector being provided with a similar notch 65, adapted to fit beneath said T-end. The set-wise size of the mold cavity is obtained by limiting the backward throw of the ejector 60, and for this purpose I provide an 95 abutment 66 secured to the forward end of an adjusting screw 67, said screw being carried by a shaft 68 controlled by an index wheel 69. In order to aid the operator in 100 securing the proper set, the wheel 69 is provided with graduations conforming to the various predetermined adjustments, and arranged to register with a stationary pointer 70.

The crosshead 64 is reciprocated by means of a bell-crank lever 71 mounted upon a rock shaft 72 and forked at 73 to engage a pin 74 in said crosshead. The depending arm of said lever is provided with a roller 110 75 which rests upon a cam 76 provided with a protuberance 77. A spring 78 encircling the rock shaft 72 tends to hold said crosshead normally retracted.

The outlet side of the mold cavity is closed 115 by a mold slide 80 mounted to reciprocate in a guide 81 formed adjacent the forward end of the mold base. The body of said slide is deflected inwardly, that is, turned in from the straight line, to form a member 120 82 adapted to fit closely against the forward ends of the mold sections 41, 42, to close the cavity 46, being normally held in close contact with said mold sections by means of levers 83 pivotally mounted at 84 and provided with approximately flat faces bearing against the outer face of said slide, an anti-friction roller 85 being carried by said levers. To the upper ends of levers 83 is connected a link 86 passed through a guide 87, 130

a spring 88, the tension of which is controlled by a nut 89, serving to hold the flat faces of said levers firmly against the outer face of slide 80, whereby the latter will fit closely against the forward ends of the mold sections. The mold slide is also provided with an internal overhanging portion 90 provided with an opening 91. Said slide is also provided with an integral downwardly bent out-turned finger 92 for breaking the jets; an abutment 93 (see Fig. 6) is carried by the slide 80 and arranged to engage the mold block 42 in its forward movement, to limit the movement of said slide.

15 The mold slide 80 is reciprocated through the medium of a rock shaft 94 mounted in suitable bearings and provided with a cam arm 95 engaging the cam groove 96 in the rotating cam member 97. To the forward 20 end of said rock shaft is secured an arm 98 which pivotally supports a yoke 99, the latter being in turn pivoted to the slide 80, as indicated at 100. The yoke 99 is provided with a finger 101 provided with a seat for 25 one end of a tension spring 102 carried by arm 98, the tension of said spring being regulated by means of nuts 103 working on a threaded rod 104.

The matrix 110 is mounted in a carrier 30 111 (Figs. 11 and 13) arranged to reciprocate through the openings 91 in the mold slide 80. Said carrier comprises a block provided with a plurality of adjustable matrix clamping members 112 controlled by clamping screws 113. Said block is also provided with a slot 114 to receive a supporting pin 115 mounted in the forward end of an operating lever 116 mounted on a rock shaft 117. The pin 115 is provided with a tapered head 40 115' arranged to engage roller 85, whereby the arms or levers 83 are moved out of engagement with the mold slide as the matrix carrier is raised. A spring 118 encircling said shaft 117 acts to hold said matrix carrier normally retracted from the mold cavity. To the rock shaft 117 is secured a depending arm 119 provided with a pin 120, and to rock shaft 54 is secured a similar arm 121 provided with a pin 122 (see Fig. 45 18). Said pins 120 and 122 are engaged, respectively, by slots 123, 124, in a link 125 connected to a cam arm 126 arranged to engage a cam 127. The slot 124 is made longer than slot 123, whereby arm 121 will remain 50 at rest during a portion of the time that arm 119 is moving.

The metal supply mechanism comprises a metal pot 130 adapted to contain the molten metal, suitable heating devices 131 (see Fig. 2) being employed for maintaining the metal in the molten condition.

The metal injecting mechanism consists of the pump casing 132 provided with openings 133, and closed at its lower end by a plug 60 134. Mounted within the casing is a plun-

ger 135 provided with the usual nipple or outlet 136. A rock shaft 137 is mounted in suitable bearings 138 and serves to support a yoke-like lever 139 pivotally connected at its forward end to the pump casing 132, the 70 rear end of said lever being provided with a roller 140 arranged to engage a cam 141 having a depression 142. Mounted on said rock shaft is a bell-crank lever 143, one arm of which is provided with a roller 144 in 75 the path of a second depression 145 in cam 141. The other arm of said bell-crank lever is forked to receive one end of a finger 146 pivotally connected thereto, the other end of said finger being pivotally connected to a 80 depending plunger operating member 147. Said member is provided with a pin 148 arranged to enter the forked end of a lever 149, said lever being extended through casing 132 and plunger 135, and pivotally 85 mounted at 150 in a depending lug 151. The rear end of finger 146 is provided with a stud 152 which is connected by a spring 153 with a similar stud 154 on lever 143. The roller 140 of lever 139 is held normally in 90 engagement with the cam 141 by means of a yoke 155 straddling the metal pot and connected to lateral extensions 156 of lever 129. Said yoke is adjustably connected to a rod 95 157, preferably by a screw thread, said rod in turn, being encircled by a helical spring 158, one end of which bears against an adjustable abutment 159 and the other end against a stationary collar 160. To said collar is pivotally connected a spring pressed 100 latch 161 arranged to engage a lip 162 carried by a nut 163 on said rod 157, whereby the yoke may be locked in a depressed position if it is desired to render the pump inoperative. Said latch is controlled by a 105 handle 164.

After being cast the type are delivered upon a typeway comprising two guide members 165, carried by the adjustable members 166, 167, respectively. The member 166 110 is normally stationary while the adjustable member is arranged adjacent an abutment 168. The adjustment of said members is accomplished in any suitable manner, preferably by a set screw and slot connection, 115 as indicated at 169.

If desired the molds may be artificially cooled by water or other refrigerating fluid, and for this purpose I show a tank 170 from which the cooling fluid is drawn by a pump 120 171 and forced upward through a pipe 172 provided with branches 173 leading to the mold sections 41, 42, respectively. From thence the return is through pipe 174 to said tank. The pump 171 may be operated 125 by means of a sprocket chain 175 connected with the main shaft 32 in any suitable manner.

The cams 76, 97, 127 and 131 may be arranged independently, but for convenience 130

they are all shown as formed on a single member C mounted on a shaft 180, said shaft being rotated by means of a pulley 181 secured thereto and connected by a belt 182 with pulley 34. The speed of said cams may be varied in any preferred manner.

The operation is as follows:—The burner 181 is first ignited for the purpose of bringing the type metal in the pot to a molten 10 condition and to maintain the same in this state. The matrix is secured in position in the carrier 111 and the latter attached to the operating arm 116. The type ejector 60 of the desired bodywise size, and the jet 15 ejector 61 are then attached to the cross-head 64 and interposed between the mold blocks 41, 42. The filler block 45 corresponding to the bodywise size of the ejector is then inserted between the abutment 44 20 and the mold block 42, whereby the latter is accurately moved to a position to provide the proper bodywise size for the mold cavity. The setwise size of the mold cavity is obtained by adjusting the wheel 69 to 25 bring the proper markings in register with the pointer 70, and thereby moving the abutment 66 to such a position as will interrupt the movement of the ejector at the proper point to give the required size to the 30 mold cavity. After the parts have been adjusted and placed in their various positions, as described, the pump is released from the yoke 155 and the clutch lever 36 is operated to connect the various parts with the power. 35 The various cams on cam member C are arranged to act in time with each other. The crosshead 64 under the influence of spring 78 is held normally retracted with the rear end of the ejector against the abutment 66, 40 the forward end of the ejector 60, and the corresponding end of the jet ejector 62, forming one side of the mold cavity, and the mold blocks 41, 42, each forming one side of said cavity. The cam 96 is so timed 45 that the mold slide 80 is first moved to a position whereby the inturned member 82 will close the end of the mold cavity and form the fourth wall of the latter, being held tightly against the mold blocks 41, 42 by 50 the levers 83. As the mold slide reaches its position the cam 127 through link 125 rocks the shaft 117, causing arm 116 to bring the matrix carrier downwardly through the opening 91 in said mold slide. The movement 55 of the link 125 is such as to increase the tension on spring 58, thereby forcing the mold block 41 closely against the ejector while the latter is at rest, to make a tight joint and to accurately square the faces 60 of the mold cavity. As the cam member proceeds with its rotation the roller 140 drops into the depression 142, thereby rocking shaft 137 to bring the roller 144 into contact with the cam 141, and immediately 65 thereafter the said roller 144 drops into

the depression 145, and operates the pump piston to inject the molten metal into the mold cavity. It will be noted, of course, that the ends of the latter are closed by the matrix and the nipple plate, respectively. 70 Immediately after the casting operation, the lever 126 is operated to withdraw the matrix and relieve the tension on the mold block 41, allowing sufficient lateral play of the latter to permit the ejector to move freely between 75 the mold blocks. At the same time the upward movement of the matrix brings the protuberance on pin 115 into engagement with roller 85, and moves the levers 83 away from the mold slide, against the tension of spring 80 88, thereby permitting free movement of said mold slide. As soon as the mold slide is free, it is moved far enough to uncover the mold cavity and then its movement is interrupted, (the cam groove 96 being properly shaped to effect this pause in the operation), whereupon the ejector will be forced forward by cam 76 to eject the type from the mold cavity and on to the mold base 40, and with the jet in line with the jet breaker 92. 90 By this time the cam 97 operates to move the mold slide 80 to the limit of its movement, bringing the jet breaker into contact with the jet and breaking the latter off from the type body in an obvious manner. The foot 95 of the type may then be finished off in any suitable or well known manner.

The operation just described is that which is required for the casting of a single type character, and is continued as long as it is 100 desired to cast type of the particular size and style for which the mold is set. When it is desired to change the bodywise size it is only necessary to substitute an ejector 60 and filler block 45 of the requisite size; to 105 adjust abutment 66 for the proper setwise size, and to place the proper matrix in the carrier 111. Obviously these changes will require but two or three minutes at the outside, and the machine is then ready for the 110 casting operation. If it is desired to change the setwise size without altering the bodywise size, it is only necessary to adjust the abutment 66. It will also be understood, of course, that the matrix is readily changed at 115 will.

It is apparent that the range of the machine is unlimited and that all sizes of type, from the largest to the smallest, and provided with any desired type character can 120 be accurately cast, and the changes in the size of the cast accomplished with an expenditure of a minimum amount of time and labor, and without necessitating the presence of operators skilled or experienced in the art 125 of type founding.

Having thus explained the nature of my said invention, and described a manner of constructing and using the same, although without attempting to set forth all of the 130

forms in which it may be made, or all of the modes of its use, I declare that what I claim is:—

1. In a machine for casting type, a mold comprising spaced apart mold blocks, an ejector working between said blocks, a rock shaft, means carried thereby for holding one of said mold sections yieldingly against said ejector, and means for periodically operating said rock shaft to remove the pressure from said mold block.

2. In a machine for casting type, a mold comprising spaced apart mold blocks, an ejector working between said blocks, a rock shaft, a segmental member mounted thereon, and means carried by said member for holding one of said mold blocks yieldingly against said ejector.

3. In a machine for casting type, a mold comprising spaced apart mold sections, an ejector working between said sections, a rock shaft, a segmental member mounted thereon and provided with means for holding one of said mold sections yieldingly against said ejector, and means for adjusting said segmental member to vary the tension.

4. In a machine for casting type, a mold comprising spaced apart mold blocks, an ejector working between said blocks, a spring controlled rock shaft, and a finger mounted on said shaft and engaging one of said mold blocks to hold the latter normally in engagement with said ejector.

5. In a machine for casting type, a mold comprising spaced apart mold blocks, an ejector working between said blocks, a spring controlled rock shaft, a segmental member mounted on said rock shaft, and a finger carried by said member and engaging one of said blocks to hold the latter normally in engagement with said ejector.

6. In a machine for casting type, a mold comprising spaced apart mold blocks, an ejector working between said blocks, a spring controlling rock shaft, a segmental member mounted on said rock shaft, a finger carried by said member and engaging one of said mold blocks to hold the latter normally in engagement with said ejector, and means for adjusting the segmental member to vary the tension on said spring.

7. In a machine for casting type, a mold comprising spaced apart mold blocks, an ejector working between said blocks, a spring controlled rock shaft, a segmental member mounted on said rock shaft, a finger carried by said member and engaging one of said mold blocks to hold the latter normally in engagement with said ejector, a stationary

60 segmental member adjacent the first mentioned member, both of said members being provided with openings, and a securing bolt passed through coincident openings in both members.

65 8. In a machine for casting type, a mold

comprising spaced apart mold blocks, an ejector working between said blocks, a spring controlled rock shaft, a finger mounted on said shaft and engaging one of said mold blocks, to hold the latter normally in engagement with the ejector, and means for periodically rocking said shaft against the tension of its spring.

9. In a machine for casting type, a mold comprising spaced apart mold blocks, an ejector working between said blocks, a spring controlled rock shaft, means carried by said rock shaft for engaging one of said mold blocks to hold the latter normally in engagement with said ejector, and means for periodically operating said rock shaft to withdraw the tension against said mold section.

10. In a machine for casting type, a mold comprising spaced apart mold blocks, an ejector working between said blocks, and a mold slide arranged to reciprocate across the ends of said mold blocks and provided with an inwardly deflected member to close the mold cavity.

11. In a machine for casting type, a mold, and a movable mold slide provided with an inwardly deflected member arranged to close the mold cavity.

12. In a machine for casting type, a mold including a movable mold slide provided with an inwardly deflected member arranged to close the mold cavity, and a stop for limiting the movement of said slide.

13. In a machine for casting type, a mold including a movable ejector, a movable mold slide for closing the mold cavity, and a deflected finger extending from one end of said slide and forming a jet breaker.

14. In a machine for casting type, a mold including a movable ejector, a movable mold slide constructed to alternately open and close the mold cavity and provided with a jet breaker, and means for temporarily interrupting the opening movement of the mold slide in one direction.

15. In a machine for casting type, a mold including a movable mold slide provided with an inwardly deflected member to close the mold cavity, and also provided with a jet breaker.

16. In a machine for casting type, a mold including a movable ejector, a movable mold slide provided with an inturned member to close the mold cavity, and also provided with a jet breaker, and means for temporarily interrupting the movement of said slide in one direction.

17. In a machine for casting type, a mold including a movable mold slide arranged to close the mold cavity and provided with means for guiding an independently supported matrix.

18. In a machine for casting type, a mold including a mold slide arranged to close

- the mold cavity and provided with an overhanging portion forming a matrix guide.
19. In a machine for casting type, a mold including a movable mold slide provided with an inturned member arranged to close the mold cavity, and also provided with a matrix guide.
20. In a machine for casting type, a mold including a mold slide arranged to close the mold cavity and provided with a jet breaker and a matrix guide.
21. In a machine for casting type, a mold including a mold slide arranged to close the mold cavity and provided with a jet breaker and an overhanging matrix guide.
22. In a machine for casting type, a mold including a mold slide provided with an inturned member arranged to close the mold cavity, and also provided with a jet breaking finger and a matrix guide.
23. In a machine for casting type, a mold including a mold slide arranged to close the mold cavity and provided at one end with an outturned finger forming a jet breaker.
24. In a machine for casting type, a mold including a mold slide arranged to close the mold cavity, and provided with a depending, out-turned hook-like member forming a jet breaker.
25. In a machine for casting type, a mold including a movable mold slide provided with an inturned member arranged to close the mold cavity and also provided with an out-turned finger forming a jet breaker.
26. In a machine for casting type, a mold including a movable mold slide provided with an inturned member arranged to close the mold cavity and also provided with a depending out-turned hook-like member forming a jet breaker.
27. In a machine for casting type, a mold including a movable ejector, a movable mold slide provided with an inturned member arranged to close the mold cavity and with an out-turned finger forming a jet breaker, and means for temporarily interrupting the movement of the mold slide in one direction.
28. In a machine for casting type, a mold including a movable ejector, a movable mold slide provided with an inturned member arranged to close the mold cavity and also provided with a depending out-turned hook-like member forming a jet breaker, and means for temporarily interrupting the movement of the mold slide in one direction.
29. In a machine for casting type, a mold including a mold slide provided with a jet breaker, a rock shaft, connections between said slide and said rock shaft, and means for operating said rock shaft, said means being arranged to effect a temporary interruption of the movement of said slide in one direction.
30. In a machine for casting type, a mold including a mold slide provided with a jet breaker, a rock shaft, an arm secured to said rock shaft, a yoke yieldingly mounted on said arm and connected with said slide, and means for effecting a temporary interruption of the movement of said slide in one direction.
31. In a machine for casting type, a mold including a mold slide provided with a jet breaker, a rock shaft, an arm secured to said rock shaft, a yoke pivotally mounted on said arm and connected to said slide, a spring acting against said yoke, and means for regulating the tension of said spring.
32. In a machine for casting type, a mold including a mold slide provided with a jet breaker, a rock shaft, connections between said slide and rock shaft, a cam arm connected with said rock shaft, and a cam engaged by said arm, said cam being constructed to effect an interruption of the movement of said slide in one direction.
33. In a machine for casting type, a mold including a mold slide arranged to close the delivery opening of the mold cavity, means for yieldingly holding said slide in contact with the mold body, and a matrix carrier provided with means for disengaging said holding means from said slide.
34. In a machine for casting type, a mold including a mold slide arranged to close the mold cavity, pivoted arms engaging said slide, and a spring pressed rod connected to said arms, and normally holding the latter in contact with said slide.
35. In a machine for casting type, a mold including a mold slide arranged to close the mold cavity, pivoted arms engaging said slide, a spring pressed rod connected to said arms, and normally holding the latter in contact with said slide and means for automatically moving said arms against the tension on said rod.
36. In a machine for casting type, a mold including a mold slide arranged to close the mold cavity and provided with a matrix guide, and means engaging said matrix guide to hold said slide yieldingly in contact with the mold body.
37. In a machine for casting type, a mold including a mold slide arranged to close the mold cavity and provided with a matrix guide, means engaging said matrix guide to hold said slide yieldingly in contact with the mold body, a matrix carrier arranged to enter said matrix guide, and means whereby said matrix carrier will disengage said holding means.
38. In a machine for casting type, a mold including a mold slide arranged to close the mold cavity, spring pressed arms for holding said slide yieldingly against the mold body, a matrix carrier, and means whereby said matrix carrier will disengage said arms from said slide.

39. In a machine for casting type, a mold including a mold slide arranged to close the mold cavity, spring pressed arms for holding said slide yieldingly against the mold body, a roller mounted between said arms, a matrix carrier, and a pin supported by said matrix carrier and arranged to engage said roller, whereby said arms will be disengaged from said slide.
- 10 40. In a machine for casting type, a mold formed of spaced apart mold sections, an ejector working between said sections, a spring pressed rock shaft, a finger mounted thereon and engaging one of said sections, an arm depending from said shaft, and a link for periodically moving said arm.
- 15 41. In a machine for casting type, a mold, a rock shaft, an arm secured thereto, and a matrix carrier detachably secured to said arm.
- 20 42. In a machine for casting type, a mold, a rock shaft, an arm secured to said rock shaft and having a pin in its free end, and a matrix carrier provided with a slot arranged to receive said pin.
- 25 43. In a machine for casting type, a mold provided with a loosely mounted mold block, means for exerting a yielding pressure upon said mold block, a rock shaft, a matrix carrier supported from said rock shaft, and means for operating said rock shaft and simultaneously controlling the pressure upon said mold block.
- 30 44. In a machine for casting type, a mold provided with a loosely mounted mold block, a spring impelled rock shaft provided with a finger for effecting a yielding pressure upon said mold block, a matrix carrier, and means for operating said matrix carrier and also for operating said rock shaft to control the pressure upon said mold block.
- 35 45. In a machine for casting type, a mold provided with a loosely mounted mold block, a spring impelled rock shaft provided with a finger for effecting a yielding pressure upon said mold block, a second rock shaft, a matrix carrier supported therefrom, and means for simultaneously operating said rock shafts.
- 40 46. In a machine for casting type, a mold provided with a loosely mounted mold block, a rock shaft provided with means for exerting a yielding pressure upon said mold block, a matrix carrier, a rock shaft for operating the same, a single link for operating both rock shafts, and means for operating said link.
- 45 47. In a machine for casting type, a mold provided with a loosely mounted mold block, a rock shaft provided with means for exerting a yielding pressure upon said mold section, a matrix carrier, a rock shaft for operating the same, an arm depending from each rock shaft, a link having spaced apart slots engaging said arms, the slot engaging the arm on the pressure controlling shaft being longer than the other slot, and means for reciprocating said link.
- 50 48. In a machine for casting type, a matrix carrier comprising a block provided with a plurality of fingers arranged to engage the edges of a matrix plate, and screws working in said block and engaging said fingers.
- 55 49. In a machine for casting type, a mold including a mold slide arranged to close the mold cavity and provided with a matrix guide, a matrix carrier, and means for periodically inserting said carrier in said guide.
- 60 50. In a machine for casting type, a mold including a mold slide arranged to close the mold cavity and provided with a matrix guide, a matrix carrier arranged to enter said guide, and means for operating said carrier in time with said slide.
- 65 51. In a machine for casting type, a mold including a mold slide arranged to close the mold cavity and provided with an overhanging matrix guide, a matrix carrier arranged to enter said guide, and means for operating said carrier in time with said slide.
- 70 52. In a machine for casting type, a mold including a mold slide arranged to close the mold cavity and provided with a matrix guide, a matrix carrier, a rock shaft provided with means for supporting said carrier, and means for operating said rock shaft in time with said slide.
- 75 53. In a machine for casting type, a mold including a horizontally movable mold slide arranged to close the mold cavity and provided with a matrix guide, a vertically movable matrix carrier arranged to enter said guide, and means for operating said carrier in time with said slide.
- 80 54. In a machine for casting type, a mold including a mold slide arranged to close the mold cavity and provided with a matrix guide, a matrix carrier located above said slide and arranged to periodically engage said guide, and means for operating said carrier in time with said slide.
- 85 55. In a machine for casting type, a mold including a mold slide arranged to close the mold cavity and provided with a matrix guide, a matrix carrier arranged to enter said guide, means for exerting a yielding pressure upon said slide, means for operating said carrier in time with said slide, and means whereby the matrix carrier controls the application of pressure upon said slide.
- 90 56. In a machine for casting type, a mold provided with a loosely mounted mold section, a mold slide arranged to close the mold cavity and provided with a matrix guide, means for exerting a yielding pressure upon said mold section, means for exerting a

yielding pressure upon said mold slide, a matrix carrier arranged to enter said matrix guide, means for operating said carrier and simultaneously controlling the pressure upon said mold section, and means whereby said carrier will control the application of pressure upon said mold slide.

57. In a machine for casting type, a mold, an ejector therefor, a mold slide for closing 10 the mold cavity and provided with jet breaking means, means for operating the mold slide and ejector, and means for temporarily interrupting the opening movement of the mold slide in one direction during 15 the movement of the ejector.

58. In a machine for casting type, a mold, an ejector therefor, a mold slide provided 20 with an inturned member arranged to close the mold cavity and also provided with jet breaking means, means for operating said slide and ejector, and means for temporarily interrupting the opening movement of the mold slide in one direction during the movement 25 of the ejector.

59. In a machine for casting type, a mold, an ejector therefor, a mold slide arranged to close the mold cavity and provided with an 30 out-turned finger forming a jet breaker, means for operating the mold slide and ejector, and means for temporarily interrupting the opening movement of the mold slide in one direction during the movement 35 of said ejector.

60. In a machine for casting type, a mold, an ejector therefor, a mold slide arranged to close the mold cavity and provided at one 40 end with a hook-like finger forming a jet breaker, means for operating the mold slide and ejector, and means for temporarily interrupting the movement of the mold slide in one direction during the opening movement 45 of the ejector.

61. In a machine for casting type, a mold, an ejector therefor, a mold slide for closing 45 the mold cavity and provided with a jet breaker extended below the plane of said ejector, means for operating the slide and ejector, and means for temporarily interrupting the opening movement of the mold 50 slide in one direction during the movement of the ejector.

62. In a machine for casting type, a mold, an ejector therefor, a mold slide for closing 55 the mold cavity and provided with jet breaking means, means for operating the slide and ejector, means for temporarily interrupting the movement of the mold slide in one direction during the movement of the ejector, and means for adjusting the mold to 60 vary the size of the mold cavity.

63. In a machine for casting type, a mold, an ejector therefor, a mold slide for closing 65 the mold cavity and provided with jet breaking means and a matrix guide, means for operating the mold slide and ejector,

means for temporarily interrupting the movement of the mold slide in one direction during the movement of the ejector, a matrix carrier, and means for periodically bringing said carrier into engagement with said guide.

64. In a machine for casting type, a mold, an ejector, therefor, a mold slide for closing the mold cavity and provided with jet breaking means and an overhanging matrix 70 guide, means for operating the mold slide and ejector, means for temporarily interrupting the movement of the mold slide in one direction during the movement of the ejector, a matrix carrier, and means for 75 periodically bringing said carrier into engagement with said guide.

65. In a machine for casting type, a mold, an ejector therefor, a mold slide for closing the mold cavity and formed with an overhanging portion provided with an opening 80 forming a matrix guide, means for operating the mold slide and ejector, means for temporarily interrupting the movement of the mold slide in one direction during the movement of the ejector, a matrix carrier, and means for 85 periodically bringing said carrier into engagement with said guide.

66. In a machine for casting type, a mold, an ejector therefor, a mold slide for closing 90 the mold cavity and provided with jet breaking means and a matrix guide, means for operating the mold slide and ejector, means for temporarily interrupting the movement of the mold slide in one direction during the movement of the ejector, a matrix carrier, and means for 95 periodically bringing said carrier into engagement with said guide.

67. In a machine for casting type, a mold, an ejector therefor, a mold slide for closing the mold cavity and provided with jet breaking means and a matrix guide, means for operating the mold slide and ejector, 100 means for temporarily interrupting the movement of the mold slide in one direction during the movement of the ejector, a matrix carrier, a rock shaft provided with means for supporting said carrier, and means for operating said rock shaft in time 105 with said slide.

68. In a machine for casting type, a mold, an ejector therefor, a mold slide arranged to close the mold cavity, a matrix carrier, said slide being provided with means for guiding said matrix carrier, and a plurality of cams arranged on a single carrier and constructed to operate said ejector, mold 110 slide, and matrix carrier in time with each other.

69. In a machine for casting type, a mold, an ejector therefor, a mold slide arranged to close the mold cavity, and a plurality of 115 cams arranged on a single carrier and constructed to operate said ejector, mold slide, and matrix carrier in time with each other.

70. In a machine for casting type, a mold, an ejector therefor, a mold slide arranged to close the mold cavity, and a plurality of 120 cams arranged on a single carrier and constructed to operate said ejector, mold slide, and matrix carrier in time with each other.

cams arranged upon a single carrier and constructed to operate the ejector and also operate the mold slide, to open the mold cavity said means being constructed to temporarily interrupt the opening movement of said slide in one direction.

70. In a machine for casting type, a mold, an ejector therefor, a mold slide arranged to close the mold cavity, a matrix carrier, said slide being provided with means for guiding said matrix carrier, molten metal mechanism, and a plurality of cams arranged upon a single carrier and adapted to operate said ejector, mold slide, matrix carrier, and molten metal mechanism in time with each other.

71. In a machine for casting type, a mold, an ejector therefor, a mold slide arranged to close the mold cavity, a matrix carrier, molten metal mechanism, and a plurality of cams arranged upon a single carrier and adapted to operate said ejector, mold slide,

matrix carrier, and molten metal mechanism in time with each other, means being provided to effect a pause in the movement of the mold slide before completion of said movement in one direction. 25

72. In a machine for casting type, a mold provided with a mold section arranged to have slight play, an ejector, a slide arranged to close the mold cavity, a resilient locking finger for said mold section, a resilient locking arm for said slide, molten metal mechanism, and means for rendering said locking finger and locking arm operative during the operation of said molten metal mechanism. 30 35

In testimony whereof, I have signed this specification in the presence of two subscribing witnesses.

ANDREW E. MILLER.
